FIG. 17

FIG. 18

FIG. 19

FIG. 20

FIG. 1 is a front elevation of a medical diagnostic instrument kit embodying my new design with the case covers in closed position;

FIG. 2 is a left side elevation thereof;

FIG. 3 is a right side elevation thereof;

FIG. 4 is a rear elevation thereof;

FIG. 5 is a top plan view thereof, the bottom plan view being identical;

FIG. 6 is a front elevation thereof with the case covers in open position;

FIG. 7 is a fragmentary front elevation of the instrument kit with the ophthalmoscope in an operational position;

FIGS. 8, 9 and 10 are fragmentary rear, right and left side elevations respectively corresponding to FIG. 7;

FIG. 11 is a top plan view corresponding to FIG. 7;

FIG. 12 is a fragmentary front elevation of the instrument kit with the retinoscope in an operational position;

FIGS. 13, 14 and 15 are fragmentary rear, right and left side elevations respectively corresponding to FIG. 12;

FIG. 16 is a top plan view corresponding to FIG. 12;

FIG. 17 is a rear perspective view of the combination battery handle-case with the instrument of FIGS. 7-11 in the folded out position and the case covers closed;

FIG. 18 is a front perspective view corresponding to FIG. 17;

FIG. 19 is a rear perspective view of the combination battery handle-case with the instrument of FIGS. 12-16 in the folded out position; and

FIG. 20 is a front perspective view corresponding to FIG. 19.

I claim:

The ornamental design for a medical diagnostic instrument kit, as shown and described.
